[57] ABSTRACT

A range shiftable motion transmitting connection between a single element type carrier and a drive lever positionable by differential mechanism to any of n discrete positions permits positioning of the type carrier to $2(n-1)$ discrete type carrier positions through utilization of a translating lever responsive to movement of said drive lever through first and second ranges of positioning movement according to the relative positions of said levers. The levers are shifted relative to one another whenever the drive lever, after having moved to one extreme position, is moved to its other extreme position.

SHIFT DEVICE FOR POSITIONING SINGLE ELEMENT TYPE CARRIERS ON TYPEWRITERS AND LIKE MACHINES

BACKGROUND OF THE INVENTION

The invention relates to a shiftable motion transmitting connection for positioning single element type carriers with several characters, or a type carrier shaped like a spherical body on the surface of which the characters are arranged in vertical rows (columns) and horizontal rows for the use on typewriters and similar machines.

With typewriters and similar machines it is often necessary to increase the amount of characters available for printing. Especially on a printer, which is used as an output device for billing machines and similar data processing equipment, it is often necessary to have special characters available which, although they can be arranged on the type carrier, require for their activation an entirely different arrangement of differential mechanism.

Positioning mechanisms for cylindrical, spherical, and prism shaped type carriers on printers and especially for automatic printers and teletypers are known. To position such type carriers in order to print a character, two different motions are required which in most cases are performed at the same time. In the case of a cylindrical type carrier a rotational motion is required to select the character from a vertical column and an axial motion to select the character from a horizontal row. To perform these positioning motions differential mechanisms are used which are known in several executions. Most of these differential mechanisms are arranged in such a way that with a given amount of input or calling members, which are activated in different combinations, a given amount of different motions are generated at the output of the mechanism. To position a character in one vertical column and position the correct horizontal row, two separate differential mechanisms are, in most cases, used whereby the amount of calling or input elements is exactly related to the amount of characters or character rows. For example, with a type carrier having 64 characters arranged on its surface in four rows with 16 characters in each row, the calling for the selection of one row of four can be achieved with two solenoids and the selection of a character out of 16 from the row selected can be achieved with four solenoids. It is obvious therefore that for the creation of various motions for positioning a type carrier only as many input members as are actually necessary are used. It is therefore not possible with printers of this kind to increase the amount of characters available for printing without far reaching changes in the design of the input member selection and differential mechanism. There is therefore no possibility to use a type carrier with more than, for instance, four rows of characters when the output of the differential mechanism provides only four positions.

SUMMARY OF THE INVENTION

The object of the invention is, without changes in the differential mechanism and calling or input members as an assembly unit, to provide for the selection of characters from a larger amount of characters and to position them for printing. By the addition of a shiftable connection as described in the example of execution of the invention, it is possible to use a type carrier with six verti-

cal columns instead of four without change of a differential mechanism which provides only four output positions.

This object is achieved according to the invention by connecting a type carrier, which is mounted rotationally on a carrier tube, with a drive lever whose position is controlled by differential mechanism, by means of a translating lever which is bistably positionable relative to the drive lever by means of the force of a spring whenever the drive lever, after moving to one extreme position, moves to its other extreme position.

BRIEF DESCRIPTION OF THE DRAWING

FIG. 1 is an isometric view of the shiftable connection to position a sphere shaped type carrier;

FIG. 2 is a side view of the shiftable connection in a stable position different from the position shown in FIG. 1; and

FIG. 3 is a table indicating energized combinations of input elements of a differential mechanism as can move a drive lever to n positions which are translated into 2 (n-1) output positions of a column selector lever.

DESCRIPTION OF PREFERRED EMBODIMENT

FIG. 1 shows a sphere shaped type carrier 1 consisting of two parts on the surface of which six vertical columns of characters 2 are arranged. The type carrier 1 is mounted on a shaft 3 which also carries a gear 4 in engagement with a rack 5 which is guided by a roller 6. The rack 5, which serves to create the rotational motion of the type carrier 1 about shaft 3, is only shown in principle and is not necessary for the description of the instant invention.

The type carrier 1 is mounted on a fork 7 which is fastened to the carrier tube 8 at the lower end of which a crank 9 is provided which has a guide slot 10. The carrier tube 8 with the type carrier 1 is mounted on a carriage 11, which is not fully shown, in a known fashion in front of a platen cylinder and can move laterally or is fixed when used with a platen cylinder mounted in a movable carriage. Also fastened to the carriage 11 is an outwardly directed mounting stud or pivot 12 carrying a drive lever 13 and a translating lever 14. As viewed in FIGS. 1 and 2 drive lever 13 has a forked guide 15 on the end of its rightwardly extending lever arm, into which the output member of a differential mechanism (not shown) fits, and also has a grooved stud 16 extending outwardly therefrom. The drive lever 13 carries on its outer or leftward extending lever arm, adjacent the end thereof, an outward extending mounting stud 17, and is also provided, between pivot 12 and stud 17, with an enlarged hole or vertical slot 18. The translating lever 14, which is also mounted on the mounting stud 12 so that it can rotate, has a grooved stud 19 extending outward from its rightward extending arm and a leftward open slot 20 in the end of its leftward extending arm. The translating lever 14 is shaped like a bridge to support a lever 21 with a ball 22 formed on it. The ball 22 is accommodated in the guide slot 10 to thereby rotate the tube 8 to move the type carrier 1 to a selected one of six columns. In the grooves of the stud 16 of the drive lever 13 and the closely adjacent stud 19 of the translating lever 14, the ends of a coiled torsion spring 23 are mounted. A shift lever 24 is pivotally mounted between its ends on the mounting stud 17 and secured with an E-ring 25 for movement in a plane parallel to and outwardly of the planes of movement of

the drive lever 13 and the translating lever 14. The shift lever 24 carries an eccentric bolt 26 on its rightward extending end the stud 27 of which reaches inward into the elongated hole 18 and the eccentric portion 28 of which rests in the slot 20 of the translating lever 14. By using a nut 29 and a screw slot 30, the eccentric 28 can be adjusted. Rollers 31 are mounted on the shift lever 24 which rests between the stops 32,33 of a carrier 34 which is mounted to the carriage 11 with screws 35.

As FIG. 1 shows, a differential mechanism (not shown) positions the drive lever 13 to n or four different positions I, II, III and IV from which $2(n-1)$ or six different positions P1 to P6 of lever 21 can be generated. According to the table shown in FIG. 3 two solenoids identified by reference M1 and M2 comprising the differential mechanism are used to generate movements which position the drive lever 13 to any one of the four positions I-IV. Thus, e.g., with only M1 energized the differential mechanism will move the drive lever 13 to position I; with both M1 and M2 energized and the differential mechanism will move the drive lever 13 to position II; with neither M1 or M2 energized the differential mechanism will move the drive lever 13 to position III; and with only M2 energized the differential mechanism will move the drive lever 13 to position IV. By use of a shiftable connection between the drive lever 13 and the carrier tube 8 according to the invention, it is possible to obtain six different output positions P1 to P6 of lever 21 thereby to position the type carrier 1 to six different vertical columns with only the four positions of the drive lever 13. The six positions of lever 21 are obtainable by changing or shifting the relative positions of the drive lever 13 and the translating lever 14 from one to another of two stable conditions. This occurs, with the help of overcentering spring 23 and shift lever 24 as will hereinafter appear, whenever the drive lever 13, after having moved to one extreme position in a range of $n-1$ positions moves to the other extreme position. This shifting thereby provides for movement of the lever arm 21 within two ranges each having $(n-1)$ or three positions corresponding to two ranges of $(n-1)$ or three positions I, II and III and IV, III and II, respectively of drive lever 13.

More particularly and with reference to FIG. 3 the position marked I of the drive lever 13 in FIG. 1 corresponds with the position P1 of the ball lever 21 and 22. From this position, the drive lever 13 can be moved into the positions II and III by means of the differential mechanism (not shown), causing the lever 21 and ball 22 to move into the corresponding positions P2 and P3. In order to move the lever 21 and ball 22, which represent the output member, into the position P6 the solenoid M2 is activated according to the table (FIG. 3). This causes the forked member 15 of the drive lever 13 to move from one of the positions in the range I to III, e.g., III into the position IV and this causes a shift of the translating lever 14 relative to the drive lever 13 into another possible and stable condition shown in FIG. 2. The shift of the translating lever 14 relative to drive lever 13 is caused by the fact that the roller 31 which is mounted on the shift lever 24 comes to rest against the lower stop 33 of the member 34 while the drive lever 13 is moving to position IV and thereby causes the shift lever 24 to move clockwise about stud 17, with the result that the translating lever 14 is moved counterclockwise by the eccentric portion 28 of stud 27. While this happens, the torsion spring 23 goes beyond

its tension point causing the translating lever 14 to rotate further counterclockwise to the FIG. 2 position at which stud 27, which normally transmits the motion of the drive lever 13 to the translating and shift levers 14 and 24, rests at the other end of the elongated hole 18 in the drive lever 13. Thus, when the drive lever 13 moves, e.g., from position III to position IV, the lever 21 and ball 22 jumps three positions, from P3 over P4 and P5 to P6. From this P6 position it is possible to generate the other positions P5 and P4 at the translating lever 14 as the drive lever 13 and the translating lever 14 are stable again relative to each other. More particularly these positions correspond with the positions III and II in the range IV, III and II of positions of the drive lever 13. Thus in the shifted position of the drive lever 13 and the translating lever 14 as shown in FIG. 2 there are now again a range $(n-1)$ of three P4, P5 and P6, of different positions available corresponding to the range II, III and IV of positions of drive lever 13. In order to get back into the first range of positions P1, P2 and P3 to position the vertical columns of characters in the left area of the type carrier 1 another shift is required which is achieved by movement of the roller 31 against the upper stop 32 incident to movement of drive lever 13 to position I. Again the drive lever 13 will move one distance, e.g., from position II, corresponding to output position P4 to position I while the lever 21 and ball 22 mounted on the translating lever 14 will jump three positions from the output position P4 to the output position P1.

Through the shiftable connection according to the invention, it is possible to increase considerably the amount of characters which can be positioned at a type carrier without changing the differential mechanism and the calling elements, e.g., solenoids, clutches, etc. The system is not limited to generate six mechanism positions out of four but can just as well be used to generate for instance fourteen mechanism positions out of eight. The principle to use a shiftable connection to position the whole system into a different area remains the same. As can be seen from the above, it is possible to save in this way a lot of costly parts and it is furthermore possible by small changes to adapt existing printers in such a way that as a result a considerable amount of additional characters can be used for printing. In the example according to the invention, the amount of characters are increased from 64 to 96.

The invention claimed is:

1. In a printing machine having a single element type carrier on which columns of type characters are arranged in two areas, each of which has $n-1$ columns, a drive lever movable to n positions, translating lever means connected to said drive lever for movement thereby, said translating lever means being shiftable to one or another stable position relative to said drive lever whenever said drive lever after having been moved to one extreme position is moved to the other extreme position, said translating lever means in one stable position being movable with said drive lever through a first range of $n-1$ positions corresponding to a range of $n-1$ positions of said drive lever which includes said one extreme position of said drive lever, and in said other stable position being movable by said drive lever through a second range of $n-1$ positions corresponding to a range of $n-1$ positions of said

drive lever which includes said other extreme position of said drive lever,
and means connected to said translating lever means to position a selected column of type characters corresponding to one of said 2 ($n-1$) positions.

2. In a printing machine having a single element type carrier in which columns of type are arranged in two areas,
a drive lever having a range of n positions including first and second limit positions,
a translating lever connected to position said type carrier,
means connecting said drive and translating levers whereby movement of said drive lever through a first range of $n-1$ positions, which includes said first limit position, will carry the translating lever through a corresponding first range of $n-1$ positions, and movement of said drive lever beyond said first range of positions to said second limit position causes relative movement of said drive and translating levers whereby movement of said drive lever thereafter through a second range of positions, which includes said second limit position, will carry the translating lever through a second corresponding range of $n-1$ positions, each of said 2 ($n-1$) positions corresponding to a column of type in said two areas.

3. In a printing machine having a single element type carrier on which columns of type characters are arranged in two areas, each of which has $n-1$ columns,
a drive lever positionable to any of n positions,
a translating lever connected to and movable in response to drive lever movement to position a selected column within one or the other of said areas on said type element from which a type character may be positioned for printing,
means connecting said drive and translating levers whereby, whenever said drive lever after having been moved to one extreme position moves to another extreme position, the position of said translating lever is shifted relative to said drive lever and is thereafter movable thereby through one or another range, according respectively to the relative positions of said drive and translating levers, of $n-1$ positions corresponding to columns within said areas of said type carrier,
and means connecting said translating lever to said type carrier.

4. A machine as recited in claim 3 wherein said drive and translating levers are mounted on a common pivot, and wherein said means connecting said drive and translating levers comprises a torsion spring connected between said drive and translating levers operative to maintain and to shift their relative positions whenever said drive lever after having moved to one extreme position moves to another extreme position.

5. A machine as recited in claim 4 wherein said means connecting said drive and translating levers includes a shift lever pivoted on said drive lever and movable toward an abutment whenever said drive lever after having moved to one extreme position moves to

another extreme position thereby to shift the positions of said drive and translating levers relative to one another, said shift lever having a connection with said translating lever.

5 6. In a typewriter having a single element type carrier having characters arranged in columns and rows and positionable to present a character opposite a printing position,
a drive lever positionable to n positions,
means connected to said type carrier movable to 2 ($n-1$) positions to position one of 2 ($n-1$) columns of characters on said type carrier opposite a printing point in response to movement of said drive lever comprising,
a translating lever,
and means including a torsion spring connecting said drive and translating levers and operative to hold said drive and translating levers for movement together through one or another of two ranges of movement, each of said ranges corresponding to $n-1$ columns of characters on said type carrier,
said means connecting said translating and drive levers being operative to switch the positions of said drive and translating levers relative to one another for operation together thereafter through one or the other range of movement when, after movement of said drive lever to one of its extreme positions, said drive lever is moved to its other extreme position.

10 7. In a typewriter as recited in claim 6 wherein said drive and translating levers are pivoted between their ends on a common fixed pivot rod,
a pivot stud extending from one end of said drive lever,
a switching lever pivoted intermediate its ends on said pivot stud,
a drive stud on one end of said switching lever engaged with said translating lever to transmit the motion of said drive lever to said translating lever, and abutments positioned to block movement of said switching lever thereby to cause relative movement of said drive and translating levers by said torsion spring incident to movement of said drive lever to one extreme position after having previously been moved to its other extreme position, and
a slot in said drive lever for reception of said drive stud to limit the relative movement of said drive and translating levers.

15 8. In a printing machine having a single element type carrier provided with 2 ($n-1$) columns of characters, means for moving said type carrier to any of said columns,
a drive lever movable to n positions,
and means connecting said drive lever to said carrier moving means to position columns within one or another discrete range of $n-1$ columns,
said connecting means being movable through one or the other discrete range of $n-1$ positions according to the last movement of said drive lever from one to the other extreme of said n positions.
